UNITED STATES PATENT OFFICE.

HARRY C. CLAY, OF COLUMBUS, INDIANA, ASSIGNOR TO THE REEVES & COMPANY, OF SAME PLACE.

DESIGN FOR A TRACTION-WHEEL.

SPECIFICATION forming part of Design No. 32,799, dated June 5, 1900.

Application filed January 29, 1900. Serial No. 3,240. Term of patent 14 years.

To all whom it may concern:

Be it known that I, HARRY C. CLAY, a citizen of the United States, residing at Columbus, in the county of Bartholomew and State 5 of Indiana, have invented and produced a new and original Design for Traction-Wheels, of which the following is a specification.

The accompanying drawing illustrates my invention.

- 10 In the drawing, 1 indicates the rim, upon which are mounted two series of cleats 2 and 3. Each one of the cleats 2 extends from one edge of the face of the rim toward and beyond the medial line thereof at an angle to the axis of 15 the wheel. Each of the cleats of the series 3 extends from the opposite edge of the face

of the rim toward and beyond the medial line thereof and at an angle to the axis of the wheel. The cleats of the two series are arranged alternately, so that their inner ends 20 overlap, as shown.

The essential feature of my design consists of the two series of angularly-arranged overlapping cleats upon the face of the rim.

I claim as my invention—

25 The design for a traction-wheel, substantially as shown and described.

HARRY C. CLAY.
